DISPLAY RACK

Maurice Cohen, 3580 NW. 52nd St.,
Miami, Fla. 33142

Filed Apr. 7, 1972, Ser. No. 242,283

Term of patent 14 years

Int. Cl. D6—99

U.S. Cl. D6—176

FIG. 1 is a perspective view of a display rack showing my new design;

FIG. 2 is an elevational view thereof; and

FIG. 3 is a top plan view thereof.

I claim:

The ornamental design for a display rack, substantially as shown.
